(57) **CLAIM**

The ornamental design for a beverage dispensing valve, as shown and described.

DESCRIPTION

FIG. 1 is a front, top and right side perspective view a beverage dispensing valve showing my new design;

FIG. 2 is a front elevation view thereof;

FIG. 3 is a rear elevation view thereof;

FIG. 4 is a right side elevation view thereof;

FIG. 5 is a bottom plan view thereof;

FIG. 6 is a top plan view thereof; and,

FIG. 7 is a front, top and right side perspective view thereof, in use condition.

The broken lines shown in FIGS. 2, 3, and 5-7 are included for the purpose of illustrating unclaimed portions of beverage dispensing valve and form no part of the claimed design. The broken lines shown in FIG. 7 are included for the purpose of illustrating an unclaimed environmental structure of beverage dispensing valve and form no part of the claimed design.
